UNITED STATES PATENT OFFICE.

JOHN P. ODGERS, OF PHILADELPHIA, PENNSYLVANIA, ASSIGNOR TO THE
A. M. COLLINS MANUFACTURING COMPANY, OF SAME PLACE.

DESIGN FOR A CARD-MOUNT.

SPECIFICATION forming part of Design No. 29,590, dated November 1, 1898.

Application filed June 14, 1898. Serial No. 683,443. Term of patent 7 years.

To all whom it may concern:

Be it known that I, JOHN P. ODGERS, a citizen of the United States, residing in Philadelphia, Pennsylvania, have invented and produced a certain new and original Design for Card-Mounts, of which the following is a specification.

My design is fully shown in the accompanying drawing, which represents a card-mount having thereon the impression constituting the design.

The essential feature of the design consists in the card-mount having the impression thereon shown in the accompanying drawing.

At the base of the impression is a rib 1 with central projection 2, and spanning the latter is an arch-shaped figure 3 and beyond this figure an aigret 4. At each side are scrolls 5,

the inner scrolls of each series being heavier than the outer ones and being filled in with curved lines. The space between the rib 1, arch 3, and side scrolls 5 is filled in with cross-hatching.

Having thus described my invention, I claim and desire to secure by Letters Patent—

The design for a card-mount substantially as described and as shown in the accompanying drawing.

In testimony whereof I have signed my name to this specification in the presence of two subscribing witnesses.

JOHN P. ODGERS.

Witnesses:

F. E. BECHTOLD,
JOS. H. KLEIN.
